ADVERTISING FRAME

Application filed February 24, 1931. Serial No. 517,966.

My present invention has reference to a display frame for theatrical or other posters.

An object of the invention is the provision of a display frame for posters or like advertisements of a construction that will effectively sustain and stretch the poster therein without the employment of tacks or paste and without damage to the poster.

A further object is the provision of a frame 10 in which the holding means for the poster are in the nature of hinged strips, each provided with impinging elements to engage with the poster for holding the same in the frame when the strips are swung over the poster, 15 the said strips, when swung to closed position, having abutting or interfitting ends and edges to present not only a smooth outer surface but for holding all the strips in interlocking engagement, together with means for 20 locking one of the strips in a manner that will not only hold the strips against each other but which is applicable to swing the last mentioned strip to open position so that all of the strips may be thereafter separately 25 swung to open position to permit withdrawal of the poster in an uninjured condition and the replacement of another poster.

A further object of the invention is the provision of a frame for this purpose so constructed as to insure against the warping of the hinged strips that provide the holding means for the poster.

The invention will be fully and comprehensively understood from a consideration of 35 the following detailed description when read in connection with the accompanying drawings which form part of the application, with the understanding, however, that the improvement is capable of extended application 40 and is not confined to the exact showing of the drawings nor to the precise construction described and, therefore, such changes and modifications may be made therefrom as do not affect the spirit of the invention nor exceed the scope thereof as expressed in the appended claims.

In the drawings:

Figure 1 is a front elevation of the improvement with a poster arranged therein.

Figure 2 is an enlarged detail elevation of

one of the corners of the frame to illustrate a construction for preventing the warping of the strips.

Figure 3 is an enlarged sectional view approximately on the line 3—3 of Figure 1. 55

Figure 4 is a sectional view approximately on the line 4—4 of Figure 5.

Figure 5 is a sectional view approximately on the line 5—5 of Figure 4.

Figure 6 is a detail sectional view taken on line 6—6 of Figure 2 to illustrate the construction of the lower edges of the side strips and the manner in which the lower strip is swung to open position when the locking device is brought to unlocking position. 60 65

Figure 7 is a detail perspective view looking toward the inner face of one of the strips.

The body 1 of the frame is preferably of rectangular formation and the same may be 70 constructed of wood, metal, or any other desired material. The back of the frame is indicated by the numeral 2 and is, of course, secured to the inner faces of the stiles and rails that comprise the frame proper. The body 75 of the frame may be suitably ornamented and preferably bears thereon the name of the theater or other place in which the show or performance suggested by the poster is being played.

Before proceeding with further details of 80 my invention it may be well to state that theaters are given credit for posters they return to poster exchanges, providing such posters are not injured. Ordinarily the 85 posters are tacked in the frame. The tacking is not only a tedious job but the posters are not sufficiently stretched so that they are frequently injured by the wind and it will be also apparent that the removal of the tacks 90 is likewise tedious. Very frequently the poster is torn from the tacks and the tacks thereafter indiscriminately replaced when another poster is placed in the frame. To protect posters, the frames are frequently provided with a glass cover plate; but this does not relieve the tedious task of tacking the poster in the frame and the removal of such tacks in order to preserve the poster when it is removed from the frame. In other instances the theatrical companies have posters 95 100

pasted in the frames or on billboards so that the advertising value of the posters is not lost, but such posters must be torn off the frames or bill-boards and lose their return value. 5 Still again some concerns have resorted to a facing of wire mesh but this is mostly to save the expense of glass as both the poster and the mesh must be tacked in the frame. In 10 both the tacking and the pasting of posters care must be taken that the posters are sufficiently stretched, which frequently results in the tearing of the posters. It will be noted, as the description progresses, that the posters are easily and quickly arranged in the frame 15 1 in accordance with my invention without injury to the posters and that the said posters are automatically stretched a limited amount when positioned in the frame.

To the inner edges of the vertical stiles and 20 upper and lower rails provided by the frame 1 I hinge strips. The strips may be of wood or of metal. For distinction the upper strip is indicated by the numeral 3 and has its inner edge beveled. The side strips are indicated by the numerals 4 and likewise have their inner edges beveled and the upper ends thereof are beveled corresponding to the beveled inner edge of strip 3 as indicated at 5 to contact with the beveled inner edge of the 25 strip 3 when the strip 3 is first swung to closed position and the strips 4 are thereafter swung within the frame also to closed position. The lower ends of each of the strips 4 are notched as indicated at 5^a and this construction 30 may advantageously be, and preferably is, utilized on the ends of the strip 3. The lower strip is indicated by the numeral 6 and preferably has its inner edges beveled. Both ends of this strip are beveled similar to the 35 beveled inner edge of the strips 4 as indicated at 7 to contact with the beveled inner edges of the strips 4. Thus it will be seen that when the strips are swung to closed position within the frame a smooth surface is afforded between the strips and contacting end portions 40 thereof. Moreover, as each strip after the upper strip 3 is swung to closed position, it will exert a downward and outward pressure upon the preceding closed strips, assuring 45 positive engagement between said strips and the poster. The inner face of each of the strips, that is, the faces of the strips positioned next to the poster, is reduced in thickness from a point adjacent its inner edge to its 50 outer edge by beveling as indicated by the numeral 8 or by rabbeting, to provide a limited area of contact with the poster, and the inner or hinged edges of the said strips may be rabbeted or the frame members may be and 55 preferably are grooved, as at 9, from their inner faces to points adjacent their outer faces to afford spaces between the outer edges of the strips and the members comprising the frame. By this construction a defined contacting 60 zone is provided on the inner face of 65

each strip adjacent the outer edge thereof adapted for engagement with the poster and the space afforded by the grooves 9 avoids binding or sticking of the strips against the frame. The inner face of each of the strips, 70 within the contacting area thereof, has imbedded therein pins or like impinging elements 10 whose ends project a suitable distance beyond the inner faces of the said strips and the said ends of the pins or impinging elements are designed to be received in the depressions 11 formed in the back 2 of the frame when the said strips are swung into the frame. 75

The bottom strip 6 has fixed preferably centrally on its outer or hinged edge the body portion of a keeper 12. A flange provided on the keeper is slotted, as at 13, and is projected into an opening 14 that is provided centrally on the inner face of the lower rail of the frame 1. In this opening there is fixed to the said lower rail of the frame 1 a latch casing 15. The upper face of the latch is open and the ends, from the said upper face, are also open for a suitable distance. As a matter of fact, the ends are in the nature of lugs or blocks, as disclosed in Figure 4 of the drawings. Between the connecting blocks for the sides of the casing 15 there is arranged the combined lock and opener element for the lower strip 6. This member includes a body portion that is provided with a rounded hub 16 which finds bearing in round openings in the sides of the casing 15 and is received through a round opening in the lower rail of the frame 1. The body of the combined lock and rail 80 opener is flat and includes two arms of different lengths which extend angularly from the hub. The short arm is indicated by the numeral 17 and has an angle end 18 to enter the keeper 12 when the hub 16 is turned to one position. Thus the arm and its end 18 provide a hook-like catch for locking the strip 6, and consequently the remaining strips, in 85 closed and contacting position. The longer arm 19 has its outer end rounded and, when the hub 16 is turned to release the locking element or latch the said rounded end will ride under the body plate of the keeper 12 and as a result will cause the strip 6 to be swung on 90 its hinges at an outward angle with respect to the frame 1. The hub 16, or at least the portion thereof that extends through the bearing opening in the lower frame member 1 is in the nature of a barrel, the same being provided, in the showing of the drawings, with a triangular bore 21 that is designed to receive therein the cross sectionally triangular bit 22 of a key 23. The key is, of course, removable and the bit 22 as well as the key slot 21 may 95 be of different desired shapes. 100

The strips of the improved frame have their inner or hinged edges beveled or cut at inward inclinations from one of their hinges to their ends, as indicated in the drawings by the numeral 24. This prevents the 105

binding of the strips against the frame if said strips should swell or warp. While the hinged edges of the strips may be beveled from the point of application of the hinges to the ends of said strips, it is to be understood that the object of such beveling may be obtained by other constructions. It has been found that the hinging of said strips to the frame so as to provide a slight clearance between these parts is sufficient to effect the function hereinabove set forth. With either form of construction, that is, with the bevels 24 or with the uniform spacing of the strips from the frame, the portion of the strip from the hinge end adjacent said hinge may readily yield under pressure. Therefore, as pressure is exerted upon one strip by overlapping strips the first strip is forced into intimate contact with the poster in the frame and the ends of said strips may yield transversely under the thrust exerted by the beveled ends of said overlapping strips, thereby avoiding excessive frictional binding of said first strip between the frame and the overlapping strips.

While I have stated that the inner faces of the strips are beveled, the said beveled portions terminate a suitable distance inward from the outer edges of the said strips and, therefore, merge into flat surfaces which are indicated in the drawings by the numeral 25, and it is through these flat surfaces that the impinging elements 10 are inserted. Also, the outer walls provided by the grooves or depressions 11 are arranged angularly so that the impinging elements, when the strips are swung to closed position, can sweep over these walls without contacting therewith.

In operation the strips are swung outwardly on the frame 1. A poster 26 is arranged in the frame. The upper strip 3 is first swung to closed position. The impinging elements thereon will engage with the poster to hold the same properly in the frame. The side strips 4 are then swung closed. The impinging elements 10 on the side strips will engage with the poster and perforate the same and the closing of the side strips will cause the said impinging elements to draw or stretch the poster. The lower strip 6 is now swung to closed position, the impinging elements thereon engaging with the poster and stretching the same vertically. The key is now inserted in the key opening in the barrel or hub 16 to turn the lever to bring the hooked member to engage with the keeper and the poster is effectively locked in the frame and sustained therein in a proper stretched condition without injury to the poster. The poster can be as readily removed by again inserting the key in the key opening of the element 16, turning the same to cause the arm or finger 19 to partly swing the strip 6 to open position. Swinging of the strip 6 toward open position is facilitated by the

notches 5^a in the lower ends of the stiles 4 since the surface of contact and hence the frictional resistance of the ends of strip 6 on the outer edges of stiles 4 is reduced. Similarly, the employment of corresponding notches in the strip 3 will facilitate outward swinging movement of the stiles 4. Moreover, such notches provide convenient finger holds for more readily swinging the strips 3 and 4 to open position. Except for the small apertures made by the impinging elements 10 the poster is not in any way damaged and the apertures therethrough do not impair the exchange value of the poster.

It is, of course, to be understood that the drawings merely illustrate a satisfactory embodiment of the invention. The strips may be of different shapes from those disclosed by the drawings and any of the said strips may provide the locking or key strip instead of the strip 6 as disclosed by the drawings. It is apparent, furthermore, that perforating pins need not, necessarily, be employed as the impinging elements but that non-perforating elements may be utilized as well.

Having described the invention, I claim:

1. A frame for posters or the like having strips hingedly secured to the inner edges thereof and certain of said strips having bevelled ends for lapping engagement with correspondingly bevelled edges of the other strips when the strips are swung to closed position, means for locking one of the strips having bevelled ends to the frame for likewise holding the remaining strips closed in the frame, said locking means having an extension adapted to contact with the said strip to swing the same to open position when the locking means is released.

2. A frame for posters or the like having top, side and bottom strips hingedly secured to the inner edges thereof, all of said strips having their inner edges beveled, said side strips having bevelled upper ends to engage with the beveled inner edge of the top strip when the strips are closed, the bottom strip having bevelled ends to engage with the beveled inner edges of the side strips when in closed position, impinging elements on all of the strips and the frame having depressions to receive the impinging elements therein, all of said strips having their inner faces bevelled from a point adjacent their inner edges to their outer edges, the inner edges of the frame being rabbeted and means for locking the lower strip to the frame.

3. A frame for posters or the like, having top, side and bottom strips hingedly secured to the inner edges thereof, all of said strips having their inner edges beveled, the side strips having bevelled upper ends thereof to engage with the beveled inner edge of the top strip when the strips are closed, the bottom strip having bevelled ends to engage with the beveled inner edges of the side strips when

in closed position, impinging elements on all of the strips and the frame having depressions to receive the impinging elements therein, all of said strips having their inner faces bevelled from a point adjacent their inner edges to their outer edges, the inner edges of the frame being rabbeted and means for locking the lower strip to the frame, certain of the strips having their outer edges bevelled from the hinges to the ends thereof.

4. A frame for posters or the like, having top, side and bottom strips hingedly secured to the inner edges thereof, all of said strips having their inner edges beveled, the side strips having bevelled upper ends to engage with the beveled inner edge of the top strip when the strips are closed, the bottom strip having bevelled ends to engage with the beveled inner edges of the side strips when in closed position, impinging elements on all of the strips and the frame having depressions to receive the impinging elements therein, all of said strips having their inner faces bevelled from a point adjacent their inner edges to their outer edges, the inner edges of the frame being notched, certain of the strips having their outer edges bevelled from the hinges to the ends thereof, a keeper carried by the lower strip, a hooked element in the lower portion of the frame to engage with the keeper, a hub on said element, a frame in which the hub is journaled and said hub having its outer portion likewise journaled through an opening in the frame, an arm extending angularly from the hook and of a greater length than the hub and a key member to engage with the hub for turning the same to bring the hook into or out of the keeper and when the hook is brought to its last named position to bring the arm into contact with the lower strip to swing the same to partly open position.

5. A display frame for posters and the like having rectangularly arranged stiles and rails, a backing member extending between said stiles and rails and secured to the undersides thereof, strips extending parallel and hinged respectively to said stiles and rails so as to bear in closed position upon said backing member and means carried by said strips effective in the closing movement thereof to engage and exert a pull upon a poster positioned within said frame for the purpose set forth.

6. A frame for posters or the like having top, side and bottom strips hingedly secured to the inner edges thereof, all of said strips having their inner edges beveled, said side strips having bevelled upper ends to engage the beveled inner edge of the top strip when in closed position, impinging elements on all of the strips and the frame having depressions to receive the impinging elements therein, all of said strips having their inner faces bevelled from a point adjacent their inner edges to their outer edges, the inner edges of the frame being rabbeted and means for locking the lower strip to the frame, certain of the strips having their outer edges bevelled from the hinges to the ends thereof.

edges to their outer edges, and means for locking the lower strip to the frame.

7. A frame for posters or the like having rectangularly arranged stiles and rails, strips hinged to said stiles and rails, said strips having impinging elements adapted to engage a poster placed in said frame, and depressions provided in said frame adapted to receive said impinging elements, said depressions being substantially larger than the diameter of said elements, whereby said elements are adapted to exert a drawing action upon said poster in the closing movement of said strips. 70 75

8. A frame for posters or the like, having
stiles and rails, top, side and bottom strips
hinged within said frame to the inner edges
of said stiles and rails, said side strips in the
poster retaining position of the strips being
arranged with their upper ends exerting a
downward and outward pressure upon the
top strip and said bottom strip being arranged
to exert a downward and outward pressure
on the lower ends of the side strips, portions
of the outer edges of said top and side strips
being spaced from said frame for the purpose
set forth.

9. A frame for posters or the like having hinged top, side and bottom strips, said side strips overlapping said top strip and the bottom strip overlapping said side strips, said top and side strips being provided with finger grips, said finger grips being concealed in the operative position of said strips by the overlapping portions of said side and bottom strips. 95 100

10. A frame for posters or the like having hinged top, side and bottom strips, certain of said strips overlapping another of said strips and being overlapped by said remaining strip in the closed position of said strips, and means for locking said last mentioned strip whereby to lock the other strips, said locking means comprising a locking member and an angularly positioned finger of greater length than said locking member and being movable in one direction to lock said strips and movable in the opposite direction to release said locking strip and to move the latter toward open position.

In testimony whereof I affix my signature 115
